United States Patent Office.

OSCAR L. ROBINSON, OF OWASSO, MICHIGAN.

Letters Patent No. 66,889, dated July 16, 1867.

IMPROVED CHERRY-STONER.

The Schedule referred to in these Letters Patent and making part of the same.

TO ALL WHOM IT MAY CONCERN:

Be it known that I, O. L. ROBINSON, of Owasso, in the county of Shiawassee, and State of Michigan, have invented a new and improved Cherry-Stoner; and I do hereby declare that the following is a full, clear, and exact description thereof, which will enable others skilled in the art to make and use the same, reference being had to the accompanying drawings forming part of this specification, in which—

Figure 1 is a side elevation, partly in section, of my improved machine for stoning cherries.

Figure 2 is a horizontal sectional view of the same, the plane of section being indicated by the line $z-z$, fig. 1. Similar letters of reference indicate like parts.

This invention relates to an apparatus in which one horizontal receiving-plate is employed, which is provided with concave depressions or countersinks, wherein the cherries are held. Each countersink is perforated with a hole large enough to allow the cherry-stone to pass through. Above the receiving-plate is arranged another plate of similar dimensions, which is also provided with countersinks, so that when it is placed upon the receiving-plate the countersinks in both will form spherical chambers of sufficient dimensions that a cherry can lie in each chamber without being pressed. From the centre of each countersink in the upper plate is suspended a punch, which, when the two plates are brought together, will pass through the cherry in the countersink of the receiving plate, and will force the stone through the hole in the countersink of the receiving-plate, while the body of the cherry will remain in the aforesaid chamber.

A represents a frame, consisting of two upright supports or posts, $a a$, held on a horizontal bed, b . A V-shaped groove is formed on the inner side of each post a , in which corresponding bars, $c c$, fit, which are part of a sliding-frame, B. The latter is provided with a vertical rack, d , and the teeth of a toothed segment, e , which is attached to a lever, C, mesh into the teeth of the rack, as is clearly shown in fig. 1. The lever C is pivoted to a stud, f , which projects from the bed b . Thus, by depressing the outer end of the lever C the frame B will be elevated, and vice versa, the latter being guided and steadied by the grooves in the uprights a . To the top of the frame B is firmly secured a plate, D, made of wood or iron, or other suitable material, and of hexagonal or other suitable shape. Being attached to the frame C, the plate D will be raised or lowered by means of the lever C, as may be desired, but it cannot move sideways. A number of depressions or countersinks, $g g$, are formed in the plate D, the bottom of each of which is perforated. Above the plate D is arranged another similar plate, E, which is made of the same shape as the former, and is provided with countersinks $h h$, which correspond to those in the plate D in such a manner that when the faces of the two plates are made to touch, the countersinks will form vertical chambers, as is clearly shown in fig. 1. The plate E is pivoted by a pin, i , to one of the uprights, a , the pin passing through a lug, K, which is formed on the plate, into the upper surface of the upright. The plate E can thus be swung around on the pin i , so as to completely uncover the plate D. Flanges l and o are formed around the plates D and E, respectively, which prevent their being brought too close together. In each of the countersinks $h h$ is secured a vertical pin, m , which projects downward, and the lower end of which fits through the hole in the corresponding countersink g , when the plates D and E are brought together. The lower end of each punch or pin m is made concave, as shown in fig. 1. It is evident that the plate E may be made to slide up and down instead of the plate D, and the former or the latter may be made to swing in that case. The fruit to be stoned is placed into the countersinks g , the plate E being swung around so as to leave the surface of the plate D open or exposed. The latter is lowered. The plate E is then swung around, so as to be directly above the plate D, and is locked by a lug, n , attached to E, fitting into a slot in that upright a , which is opposite to the one to which the plate E is pivoted. The lower plate is then raised towards the plate E by means of the lever C, and the punches m pass through the centre of the fruit, and hold the stones in the proper direction by means of the countersinks in their ends, and force the same through the holes in the countersinks g . The plate D is then again lowered, and the fruit will be found strung upon the punches, and can, after swinging the plate E around, be swept off the punches by any suitable device. A perforated tin plate, that operates by means of a latch on one side and a hinge on the other, when secured to the under surface of the plate E, would best answer the purpose of removing the stoned cherries from the punches.

What I claim as new, and desire to secure by Letters Patent, is—

1. Driving the stones at once out of a number of cherries by means of a series of punches, *m*, which are made to pass through the cherries, the latter being placed upon a disk or plate, *D*, which is provided with perforated countersinks, substantially as and for the purpose herein shown and described.

2. The plates *D* and *E*, when made as described, in combination with the frame *A* and lever *C*, all made and operating substantially as herein shown and described.

OSCAR L. ROBINSON.
